UNITED STATES PATENT OFFICE.

EDWARD C. GARDNER, OF ABINGTON, MASSACHUSETTS.

HEEL-PLATE FOR BOOTS AND SHOES.

SPECIFICATION forming part of Letters Patent No. 256,311, dated April 11, 1882.

Application filed October 19, 1881. (Model.)

To all whom it may concern:

Be it known that I, EDWARD C. GARDNER, of Abington, in the county of Plymouth and State of Massachusetts, have invented a new and useful Improvement in Heel-Plates for Boots and Shoes, of which the following is a full, clear, and exact description.

Reference is to be had to the accompanying drawings, forming a part of this specification, in which similar letters of reference indicate corresponding parts in all the figures.

Figure 1 is a perspective view of my improvement shown as applied to a boot-heel. Fig. 2 is a sectional side elevation of the metallic plate. Fig. 3 is a sectional side elevation of the leather filling. Fig. 4 is a sectional side elevation of the metal plate and leather filling, showing the said filling pressed into place.

The object of this invention is to promote the durability of heel-plates, prevent them from injuring floors and carpets, and connect the leather filling securely with the metal plate.

The invention consists in a metallic heel-plate made with a thick rim, having a smooth outer or wearing surface and a depressed or thin middle part, provided at a little distance from the rim and parallel therewith with studs, as will be hereinafter fully described.

A represents the metal part of my improved heel-plate. The metal plate A is made with a circumferential flange and a depressed middle part. The projecting edge of the flange has a smooth wearing-surface, so that it will not cut or injure a floor or carpet. The inner side of the flange of the plate A is scalloped, or has other shaped ornamental recesses and projections formed in it, to obtain an increased friction-surface to keep the leather filling B in place and at the same time make the heel ornamental.

Upon the surface of the depressed middle part of the plate A are formed projections or studs C, which may be made star-shaped, as shown in Fig. 1, or heart-shaped, or of any

other ornamental form. The studs C are arranged in a line parallel with the edge of the plate A, as shown in Fig. 1. Four (more or less) of the studs C may be omitted and holes formed through the plate A in place of the said studs C, to receive nails D for fastening the heel-plate to the heel of a boot or shoe. The heads of the nails D are made of the same shape as the studs C to give the face of the heel-plate a uniform appearance.

The filling B is made of leather or other suitable material, and has its edge recessed to correspond with the configuration of the inner side of the flange of the plate A. The filling B has holes formed through it corresponding in position with the positions of the studs C and the holes for the nails D, and corresponding in shape with the form of the studs C and the heads of the nails D. The filling B is pressed into the depression of the plate A, and is kept in place by the friction against the ornamental inner surface of the flange of the plate A and against the studs C and the heads of the nails D. The filling may be further secured in place by upsetting the ends of the studs C by blows with a hammer.

With this construction the heel-plates will be light, strong, and durable, and at the same time ornamental, and not liable to cut and injure floors or carpets.

Having thus described my invention, I claim as new and desire to secure by Letters Patent—

A metallic heel-plate having a circumferential flange with a smooth outer or wearing surface and a depressed middle part, provided with studs at a little distance from the flange and parallel therewith, the depressed portion being filled with leather or other suitable material, as set forth.

EDWARD CHESTER GARDNER.
